(57) **CLAIM**

The ornamental design for a socket tool, as shown and described.

DESCRIPTION

FIG. 1 is a left side and bottom perspective view of a socket tool according to our new design.

FIG. 2 is a right side and top perspective view of a socket tool according to FIG. 1;

FIG. 3 is a right side and bottom perspective view of a socket tool of FIG. 1;

FIG. 4 is a front plan view of a socket tool of FIG. 1;
FIG. 5 is a top plan view of a socket tool of FIG. 1;
FIG. 6 is a bottom plan view of a socket tool of FIG. 1;
FIG. 7 is a back plan view of a socket tool of FIG. 1;
FIG. 8 is a side plan view of a socket tool of FIG. 4, rotated 90°.

FIG. 9 calls out a sectional view of the front plan view of a socket tool of FIG. 4;

FIG. 10 is an enlarged detail view of the section view on FIG. 9 of a socket tool;

FIG. 11 is a front plan view of an alternate embodiment of a socket tool where the bottom cylindrical portion is shown in a short length;

FIG. 12 is a front plan view of the embodiment of FIGS. 1-10 of a socket tool where the bottom cylindrical portion is shown in a medium length; and,

FIG. 13 is a front plan view of an alternate embodiment of a socket tool where the bottom cylindrical portion is shown in a long length.
